FRANK T. POWERS, OF NEW YORK, N. Y., ASSIGNOR TO POWERS PHOTO ENGRAVING COMPANY, OF NEW YORK, N. Y., A CORPORATION OF NEW YORK.

PROCESS FOR MAKING PHOTOMECHANICAL COLOR-PRINTING PLATES.

1,272,521.

Specification of Letters Patent. Patented July 16, 1918.

Application filed July 6, 1916. Serial No. 107,843.

To all whom it may concern:

Be it known that I, FRANK T. POWERS, a citizen of the United States, and a resident of New York, in the county and State of 5 New York, have invented certain new and useful Improvements in Processes for Making Photomechanical Color-Printing Plates, of which the following is a specification.

The invention relates to processes for making printing plates, and in certain of its aspects, the invention relates more especially to processes for making color plates having a grain figure surface, although the invention is applicable to the production of some 15 other kinds of plates as well.

Objects and advantages of the invention will be set forth in part hereinafter, and in part will be obvious herefrom, such objects and advantages being realized through the 20 steps, processes and instrumentalities set forth in the appended claims.

The invention consists in the novel steps, succession of steps, processes and improvements herein shown and described.

25 The accompanying drawings, referred to herein and constituting a part hereof, illustrate one manner of carrying out my invention, the drawings being diagrammatic in character.

30 Of the drawings:

Figure 1 represents the making of a line negative from the original copy;

Fig. 2 represents the making of a line plate from the line negative;

35 Fig. 3 represents a print made from the line plate and a color blocked in on a portion thereof;

Fig. 4 represents the making of a screen figure negative from the colored print of 40 Fig. 3; and

Fig. 5 represents the making of a printing plate from the negative made in Fig. 4.

In carrying out my process in the preferred manner, it is applied to the production 45 of photo-mechanical plates for three-color or other multi-color work, and the process will be described as applied to the making of the red, blue and yellow plates from a plain line drawing or equivalent copy. It

50 will be considered that the copy is a line drawing, which is set up on the copy board 1 of the camera 2, and a plain line negative 3 is made therefrom, that is, a negative without any screen figure. From this line negative, a line plate 4 is made in any usual or

acceptable manner, which will usually consist in applying to the surface of the plate a light sensitive layer, such as albumin containing silver or chromic salts, and properly developing and etching the plate after exposure. The making of the line plate need not be described in further detail. 60

From the line plate there is taken upon paper, or other suitable medium 5, an impression 6, which impression will show the 65 copy or subject in outline. This impression is taken preferably in a blue color, or other color which is eliminable in usual photographic processes.

On this impression taken from the line 70 plate, the colors desired in the final impression or blocked in or applied as shown at 7 in Fig. 3, and this may be done by hand, or with the air brush, or otherwise, as may be desirable or convenient. So far as concerns many features of the invention, a number of impressions may be taken from the line plate referred to, and the several colors, such as the primary colors, may be blocked in or applied, the one color on one of said 75 impressions from the line plate, and another color on another of said impressions, and the third color on a third of such impressions, if desired. In one aspect of the invention, the secondary or other actual colors 80 may be blocked in or applied on the impression taken from the line plate, and suitable light filters be used to separate the primary colors in successively photographing such an impression for the several final printing plates, by the superimposed printing of 85 which plates the colored picture is produced. 90

After the colors are applied or blocked in on the impression taken from the line plate, in any of the ways mentioned, or otherwise, 95 the three color plates are made therefrom. It may be considered that the three primary colors have been blocked in on three impressions or prints taken from the line plate. In such case, a print or impression so colored 100 is set up on the copy board of the camera as indicated at 8 in Fig. 4, or otherwise positioned, and a negative thereof made in the camera by exposure of a sensitized plate through a half-tone screen, say, for use in 105 making the red printing plate. If the ordinary half-tone screen is used, there is used therewith a straight slit stop so positioned that it will produce on the negative, that is, the sensitized plate from which the negative is 110

to be made, the one way or parallel rulings but will cut out the cross or perpendicular rulings. Thus the screen figures produced in the negative will consist of one way parallel rulings, although so far as concerns certain features of the invention, this may be varied. It will be understood also, that where the impression photographed, that is, constituting the copy in this instance, is in 10 secondary colors, a proper color filter will be used.

From the negative 9 so made, a plate 10 is produced in the usual manner for half-tone plates, which is briefly to sensitize the 15 surface of a metal plate, such as copper, expose it to light under the half-tone, or screen figure negative, and then develop and etch it. Similarly, a printing plate may be made for the blue color from a suitable copy produced from an impression or print taken 20 from the line plate. With this second plate, however, the slit stop will be given a quarter turn, or changed in position by a quadrant, and thereby in the camera, the half-tone screen will produce on the sensitized 25 plate which is to constitute the negative, the one-way screen figures, that is, the parallel lines or rulings all running one way and perpendicular, that is, at right angles to the 30 screen figure lines on the first negative, or red printing plate negative, already described.

In making the yellow printing plate, the procedure will be generally the same as with 35 the red and blue plates, but the usual stop may be employed in the camera and the full screen figure, or the cross lines or rulings of the half-tone screen will appear on the negative, in the form of the usual half-tone 40 dots, varying according to the lights and shadows in the usual manner.

From these different negatives, plates are made in the usual manner, that is, in the case 45 of each negative, exposing therebeneath a sensitized metal plate, which plate is then developed and etched. These plates are then printed in superimposition in inks of the proper colors, in a well-understood manner.

What I claim as my invention and desire 50 to secure by Letters Patent is:—

1. The process of making color printing plates which comprises making a line negative from the colored copy, making a line plate from said line negative, taking a plurality of impressions from said line plate, 55 applying to these impressions, respectively, the various desired primary colors in such portions and disposition as may be desired, making screen figure negatives of the various colored impressions by making the red 60 negative with the screen rulings running one way only, making the blue negative with the screen rulings running one way only and

substantially at right angles to the rulings in the red negative, making the yellow negative with the rulings running both ways, and making the corresponding printing plates from said negatives. 65

2. The process of making color printing plates which comprises making a line negative from the colored copy, making a line plate from said line negative, taking an impression from said line plate, coloring said impression as desired, making three color plates therefrom, for red, blue and yellow, 75 making the red plate with screen rulings running one way only, making the blue plate with screen rulings running one way only and at right angles to those of the red plate, and making the yellow plate. 80

3. The process of making color printing plates which comprises making a line negative from the colored copy, making a line plate from said line negative, taking an impression from said line plate, coloring said impression as desired, making three color plates therefrom, for red, blue and yellow, 85 making the red plate with screen rulings running one way only, making the blue plate with screen rulings running one way 90 only, and at right angles to those of the red plate, and making the yellow plate with the cross rulings.

4. The process of making color printing plates which comprises making a line negative from the colored copy, making a line plate from said line negative, taking an impression from said line plate, coloring said impression as desired by hand, making three color plates therefrom, for red, blue and yellow, 95 making the red plate with screen rulings running one way only, making the blue plate with screen rulings running one way 100 only, and at right angles to those of the red plate, and making the yellow plate. 105

5. The process of making color printing plates which comprises making a line negative from a colored copy, making a line plate from said line negative, taking an impression from said line plate, applying thereto one or more colors in such portions and dispositions as may be desired, making a one color screen figure negative from said colored impression with the screen rulings running one way only, making a screen figure negative for another color with the screen figures running in a substantially perpendicular direction, and making the respective color plates from said negatives. 110

In testimony whereof, I have signed my 115 name to this specification, in the presence of two subscribing witnesses.

FRANK T. POWERS.
